UNITED STATES PATENT OFFICE.

WILLIAM H. KABLE, OF STAUNTON, VIRGINIA, ASSIGNOR TO WILLIAM GIBBS KABLE, OF SAME PLACE.

THILL-TUG.

SPECIFICATION forming part of Letters Patent No. 536,084, dated March 19, 1895.

Application filed July 24, 1894. Serial No. 518,445. (No model.)

To all whom it may concern:

Be it known that I, WILLIAM H. KABLE, residing at Staunton, in the county of Augusta and State of Virginia, have invented certain 5 new and useful Improvements in Thill-Tugs, of which the following is a specification.

My invention has relation to thill tugs of that class in which the tug proper has a hinged member arranged to be swung up 10 around the shaft and be detachably connected with the other section, to which the harness is attached.

My invention primarily has for its object, to provide a simple, cheap, and automatically 15 locking thill tug, which will snugly embrace the thill, and which can be easily and quickly operated to liberate such thill from the tug.

It also has as an essential feature, for its object, to provide a thill tug and tug holding 20 devices so arranged that the usual draft braces are dispensed with and the pulling or backing operation effected entirely by tug pressure.

A further object is to provide a tug and tug releasing devices, arranged to be operated 25 from the vehicle whereby the animal can be almost instantly released from the vehicle in case of a runaway.

With other minor objects in view, which hereinafter will appear, the invention consists 30 in such novel features of construction and peculiar combination of parts such as will be first described in detail and then be particularly pointed out in the appended claim, reference being had to the accompanying 35 drawings, in which—

Figure 1 is a view showing my improved tug devices as in use. Fig. 2 is a perspective view of my improved thill tug. Fig. 3 is a transverse section of the same, the hinged member 40 being shown down in dotted lines. Fig. 4 is a front view of my improved thill tug in position on the thill, and Fig. 5 is a perspective view of the thill guard or tug bearing member hereinafter referred to.

In its practical construction my improved 45 thill tug comprises essentially what I term a base plate or member, to which the harness straps are attached, and a hinged member which is adapted to be snugly fitted about 50 the thill, and automatically locked in engagement with the main plate, and a draft plate

or member secured to the thill against which the tug is adapted to exert its pull or push force.

Referring now to the drawings by letters, 55 A indicates the main plate formed at the top with a loop a, to which the back band or strap B, is attached and has at its edges near the lower end, loops a'a² to which the hame strap C and the breeching strap D are respectively 60 attached as clearly shown in Fig. 1. The loop members a a' a² may be connected with the plate A by rivets or cast in one piece, but are preferably formed integral with the said body and stamped out therefrom as shown. At the 65 lower end the plate terminates in hinge eye portions E, with which interlock similar portions f on the hinged thill supporting member F, which in its general contour is substantially as shown in the drawings its upper end being 70 reduced to form a locking tongue f' which when the said member is swung to its closed position will automatically be locked in engagement with the lock devices disposed at the upper end of the plate A.

The lock devices are inclosed in a casing G, 75 in practice stamped and bent up to the desired shape, which casing is secured to the main plate A by riveting or otherwise. This casing it will be observed has a pocket or recessed portion g, in which the tongue f', of the member F, is adapted to fit the side walls of such pocket forming side bearings for the said tongue, whereby to relieve the latch portion proper of the pulling strain, and in such 80 pocket is held to slide a plunger or lock member H, having a guide lip h and side extensions h' which are held in slotted ways h² which form the side walls of the pocket g.

The plunger H has a vertical extension H^x 90 which projects up above the casing, and such plunger is normally pressed downward by the spring h^x.

J indicates a cord which connects with the extension, passes through the turret ring, extends rearward and connects with an operating cord J' which passes back into the vehicle.

K indicates a keeper or draft member, the construction of which is clearly shown in Fig. 4, and its operation is best understood by 95 reference to Fig. 5. The member K comprises a base portion k which is screwed to

the under side of the thill, vertical pendent portions k' and angle brace portions k^2 which are also fastened to the thill as shown.

It will be noticed by reference to Fig. 5 the 5 hinged member F of the tug passes between the arms k' , which serves to hold the tug always to its proper position. As the tug is thus held between the arms k' , it is obvious that when the animal starts forward the member 10 F will bear against the front arm k' , and as the animal backs such tug will bear against the rear arm k , thereby effecting a push or pull action on the thills direct from the tug, dispensing entirely with the necessity of trace 15 or other draft means.

By forming the tug with a straight wall or fixed portion and hinging the member F thereto as shown such member F when released will swing entirely free from the shaft 20 and thereby allow such shafts to positively free themselves from the keepers or tugs. Furthermore by providing a draft connection (as shown at K) secured only on the under side of the shafts and leaving the edges 25 and the top practically free, the tug devices will be held for a limited free movement on the shafts and thereby avoid the danger of breaking any of the parts, as the animal

moves or twists about, which would be likely to occur, where the tug devices fitted between 30 connecting devices extending entirely around the shafts or connections will project over the top thereof and hold it rigid, as it were, within the tug loop.

Having thus described my invention, what 35 I claim, and desire to secure by Letters Patent, is—

An improved thill tug comprising a main straight plate, having loops to receive the breast collar, the girth and the breeching 40 straps, and having a housing at its upper end, provided with a central pocket or recess, a spring operated latch operating within such housing and having its tang or lock member projected into such pocket or recess, 45 and a tug supporting loop hinged to the lower end of the main plate and having a tongue, adapted to enter the aforesaid pocket and be automatically locked in engagement with the latch member all substantially as shown and 50 for the purpose described.

WILLIAM H. KABLE.
